[57] CLAIM

The ornamental design for a miniature electromechanical hour meter/counter, as shown and described.

DESCRIPTION

FIG. 1 is a perspective view of a miniature electromechanical hour meter/counter embodying the design of the invention;

FIG. 2 is a right-hand side elevational view of the hour meter/counter of FIG. 1;

FIG. 3 is a left-hand side elevational view of the hour meter/counter of FIG. 1;

FIG. 4 is a front elevational view of the hour meter/counter of FIG. 1;

FIG. 5 is a rear elevational view of the hour meter/counter of FIG. 1;

FIG. 6 is a top plan view of the hour meter/counter of FIG. 1; and,

FIG. 7 is a bottom view of the hour meter/counter of FIG. 1.

The broken line showing of two electrical cord portions is for illustrative purposes only and forms no part of the claimed design.
